TUYÈRE BLOCK

James H. Harlow, Lansdowne, Pa.

Application August 8, 1932, Serial No. 627,832

4 Claims. (Cl. 110—44)

The present invention relates to tuyères of the type that are used in underfeed mechanical stokers. The principal objects of the present invention are to cause airflow in a direction practically normal to the periphery of the tuyère at all points of air emission, to effect efficient utilization of the space along the periphery of the tuyère, to provide for a low, i. e., small pressure drop through the tuyère, to provide an efficient cooling effect, to attain a practically uniform grading or increase of the air velocity from the nose of the tuyère to the sides of the tuyère, and to provide an accurate distribution of the air around the tuyère.

Other objects of the invention will appear from the following description at the end of which the invention will be claimed.

The invention also comprises the improvements to be presently described and finally claimed.

In the following description reference will be made to the accompanying drawings forming part hereof and in which,

Figure 1 is a top or plan view diagrammatically illustrating a tuyère block.

Figure 2 is a bottom view drawn to an enlarged scale and showing so much of a tuyère block as is necessary for an understanding of the invention, and

Figure 3 is a view similar to Figure 2 illustrating a modification.

Referring to the drawings, and more particularly to Figure 2, the tuyère block has approximately the exterior outline of an oblong horseshoe, with one end straight and the opposite end curved. 1 indicates a series of marginally disposed curved vanes. These vanes define between them curved air lanes 2 of progressively decreasing and increasing cross sectional area. The entrance portions of these air lanes are disposed substantially parallel to the longer axis *a—a* of the tuyère block and they (the entrance portions) are of progressively decreasing width from the straight end portion to the curved end portion of the tuyère block. This is indicated at 3 and 4. The exit portions 5 of the air lanes are substantially normal to the peripheral contour of the tuyère block and are of substantially the same cross sectional area. 6 indicates means by which the tuyère blocks may be mounted one upon another in the usual manner with the vanes facing downward. The tuyères are usually arranged between the retorts of the underfeed stoker mechanism.

The described shape of the air lanes turns the air stream approaching from the straight end portion or flat end of the tuyère to the side caus-

ing the air to leave the tuyère substantially normal to the periphery and this assists in making the maximum use of the space provided for air admission along the periphery of the tuyère. The vanes provide the necessary cooling effect. In the described construction low resistance is effected because there are no points where the air strikes against a barrier in such a way as to cause a sudden change of direction. At the same time the air takes such a path through the tuyère that it is forced into intimate contact with the vanes insuring good cooling effect. In the performance of this result the varying width or cross section of the air lanes plays an important part because the air is forced to scour the surfaces of the vanes opposing the formation of hot air films. The gradual diminution in the width of the entrances of the air lanes toward the curved end portion of the tuyère block reduces the air velocity at the curved end portion of the tuyère block where the fuel bed is thinnest and also provides that most of the air is emitted from the sides of the tuyère where greater resistance to the air stream is provided by the fuel in the retorts. There are thus provided paths of equal resistance to the air at the sides of the tuyère block and at the curved end portion of the tuyère block, because the fuel bed is thicker at the sides of the tuyère block than it is at the curved end portion of the tuyère block, and hence the air issuing at the sides of the tuyère block must traverse a greater thickness of the fuel bed than must the air issuing at the curved end portion of the tuyère block. Providing air at high velocity on the sides and air at low velocity at the curved end portion of the tuyère block tends to burn coal in the retorts which is equivalent to increasing the effective burning area of the grate. Sufficient air is provided to cool the curved end portion of the tuyère and to provide for combustion of fuel at that point and at the same time most of the air is directed into the fuel in the retorts.

The construction and mode of operation of the modification illustrated in Figure 3 are as above described except that the vanes 1^a are discontinuous and are provided with pointed ends and in this modification the air lanes 2^a are of increasing and decreasing cross sectional area to the extent that in some places they intercommunicate.

It will be obvious to those skilled in the art to which the invention relates that modifications may be made in details of construction and arrangement and matters of mere form without de-

parting from the spirit of the invention which is not limited to such matters or otherwise than the prior art and the appended claims may require.

5 I claim:

1. A tuyère block having approximately the exterior outline of an oblong horseshoe, with one end straight and the opposite end curved, and having on one face a series of marginally disposed, curved vanes projecting up from said face of the tuyère block and defining between them curved air lanes, each of said air lanes being of progressively decreasing and increasing cross-sectional area, the entrance portions of said air lanes being each disposed substantially parallel to the longer axis of the tuyère block, said entrance portions decreasing in succession progressively in the direction from the straight end toward the curved end of the tuyère block, and the exit portions of each of said air lanes being substantially normal to the peripheral contour of the tuyère block and each being of substantially the same cross-sectional area.

2. A tuyère block having approximately the exterior outline of an oblong horseshoe, with one end straight and the opposite end curved, a series of marginally disposed, interrupted, curved vanes projecting up from one of the faces of the tuyère block, said vanes defining between them curved air lanes, said air lanes being each of progressively decreasing and increasing cross-sectional area, the entrance portions of said air lanes being each disposed substantially parallel to the longer axis of the tuyère block, said entrance portions decreasing in succession progressively in the direction from the straight end

toward the curved end of the tuyère block, and the exterior portions of said air lanes being each substantially normal to the peripheral contour of the tuyère block.

3. A tuyère block of approximately the exterior outline of an oblong horseshoe, with one end straight and the opposite end curved, a series of marginally disposed, interrupted, curved vanes projecting from one of the faces of the tuyère block, and having pointed ends and defining between them curved air lanes, said air lanes being each of progressively decreasing and increasing cross-sectional area, the entrance portions of said air lanes being each disposed substantially parallel to the longer axis of the tuyère block, said entrance portions decreasing in succession progressively in the direction from the straight end toward the curved end of the tuyère block, and the exit portions of said air lanes being each substantially normal to the peripheral contour of the tuyère block.

4. A tuyère block having approximately the exterior outline of an oblong horseshoe, with one end straight and the opposite end curved, a series of marginally disposed, curved vanes projecting from one of the faces of the tuyère block and defining between them curved air lanes, each of said air lanes being of progressively decreasing and increasing cross-sectional area, the entrance portions of said air lanes being each substantially disposed parallel to the longer axis of the tuyère block, and the exit portions of each of said air lanes being substantially normal to the peripheral contour of the tuyère block.
